TRAMMEL

George A. Reinhold Paege, Detroit, Mich.

Application June 1, 1939, Serial No. 276,905

2 Claims. (Cl. 33—158)

This application relates to measuring or drafting instruments known as beam compasses or trammels.

The principal object is to provide a beam compass or trammel of extremely simple construction for precise measurements and which is so formed that though its slide blocks may easily be moved along the beam, they will, when desired, fix themselves so firmly on the beam that they and the scribe points carried thereby will be rigid and firm with respect to the beam whereby to eliminate objectionable creeping of the point with respect to the beam. The compass is formed to be free of objections arising due to expansion or contraction of parts, or temperature or moisture change, causing dead movement.

An embodiment of the invention is disclosed in the appended drawing. In this drawing:

Fig. 1 is a cross section or end view;
20 Fig. 2 is a side view with one of the sliding blocks shown as having a scribe point therein;
Fig. 3 is a top plan view with both blocks shown as having scribe points therein.

The beam compass hereof comprises a beam 10 of wood, metal or other materials, formed solid or tubular as desired, and of the cross section of a pentagon or the like, the beam having a flat top 11 and having sides comprising portions 12 which are square to the top and portions 14 which are arranged at oblique angles to the top to meet in an apex line 15.

Slidably mounted on the beam are the slide blocks. Each of these consists of a sheet metal body having sides shaped to fit closely around the oblique sides of the beam with necessary clearance for expansion between the parallel sides and thus each slide block has two parallel portions 16 and two inclined portions 17 which meet in an apex line 18 disposed at the apex line of the beam. Aligned slots 20 in the side portions 16 of the slide blocks receive stub shafts or bearings 21 on the ends of knurled rollers 22 which are thus journaled in the slide blocks with their axes oblique to the portions 14 and 17 of the beam and blocks.

The rollers 22 are arranged to roll along the flat top of the beam. In each block is a spring 23 for pressing the roller against the flat top of the beam and for wedging the inclined surfaces 17 of the block against the inclined surfaces 14 of the beam and each spring also operates as a means for releasably holding a scribe point or pencil firmly in the slide block, all in a manner that will now be described.

Each spring consists of a flat leaf having its

center cut out to provide side portions 24 and end portions 25 and 26. The side portions 24 have lugs 27 fitting in the slots 20 and resting on the bearings 21. The end portions 25 and 26 fit under cross pins 28 which connect the side portions 16 of the blocks at their ends. The end portion 26 has a finger grip forming extension which may be pressed towards the flat top of the beam for releasing a scribe point or pencil 29 disposed in aligned holes 30 formed in the 10 portions 16 of the slide blocks. The scribe point is normally wedged into V-shaped portions 31 of such holes by bent portions 32 of the springs, for the spring is so formed that its ends tend to move toward pins 28 and its center lugs 27 15 tend to move towards the beam 10.

When the parts are mounted as shown, the slide block will be seated firmly, with its pointer, on the beam and movement of the beam and its pointer will not be accompanied by creeping or 20 objectional lateral shifting of the pointer with respect to the beam. The block may be moved longitudinally of the beam without disturbing the setting of the pointer with respect to the block merely by pushing or pulling the block along 25 the beam without touching the finger grip, using the knurled nut as a thumb roller for fine setting.

The block spring holds the pointer firm with respect to the block, but may be easily pressed 30 to release the pointer.

I claim:

1. A beam compass or trammel comprising a beam having a flat top and having sides having portions squared to the top and portions arranged at oblique angles to the top to meet in an apex line, and slide blocks comprising sheet metal bodies, each having sides shaped to fit closely around the edges of the beam and thus comprising two parallel portions and two inclined portions which meet in an apex line disposed at the apex line of the beam, a roller in each block journaled in its sides and arranged to roll along the flat top of the beam, and a spring in each block for pressing the roller against the flat top of the beam and for wedging the inclined surfaces of the block against those of the beam, and a scribe holder in the block, comprising a bent portion of the spring formed to wedge the scribe into V shaped parts of holes in the parallel sides of the block, the holes being in a line transverse to the long axis of the beam.

2. A beam compass or trammel comprising a beam having a flat top and having sides having portions squared to the top and portions arranged 55

- at oblique angles to the top to meet in an apex line, and slide blocks comprising sheet metal bodies, each having sides shaped to fit closely around the edges of the beam and thus comprising two parallel portions and two inclined portions which meet in an apex line disposed at the apex line of the beam, a roller in each block journalled in its sides and arranged to roll along the flat top of the beam, and a spring in each block for pressing the roller against the flat top of the beam and for wedging the inclined surfaces of the block against those of the beam, and a scribe holder in the block, comprising a bent

portion of the spring formed to wedge the scribe into V shaped parts of holes in the parallel sides of the block, the holes being in a line transverse to the long axis of the beam, the block having at its ends abutments under which are the ends of the spring, the latter passing over the roller, and having a finger grip extending beyond the end of the block, with the bent portion of the spring and the block holes being between the roller and that end of the block nearer the finger grip of the spring.

G. A. REINHOLD PAEGE.
